United States Patent Office

Des. 203,251
Patented Dec. 21, 1965

203,251

CONTOUR PILLOW OR THE LIKE

Abe L. Barber, Oklahoma City, Okla., assignor to A & B Instrument Co., Inc., Oklahoma City, Okla., a corporation of Oklahoma

Filed May 7, 1965, Ser. No. 85,168

Term of patent 14 years

(Cl. D3—9)

FIG. 1

FIG. 3

FIG. 1 is a top perspective view of a contour pillow embodying my new design;

FIG. 2 is a bottom perspective view thereof; and,
FIG. 3 is a side elevation view thereof.

I claim:

The ornamental design for a contour pillow or the like, as shown.
